DERMATOME

John D. Reese, Philadelphia, Pa.

Application July 7, 1947, Serial No. 759,329

2 Claims. (CL. 128—305)

1

This invention relates to surgery, more particularly to skin grafting, and has for an object to provide an improved dermatome for cutting skin grafts.

In applicant's copending application, Serial No. 618,523, filed September 25, 1945, now Patent No. 2,442,434 granted June 1, 1948, there is disclosed a dermatome of the type comprising a body member having a convex working face and a graft cutting member supported by the body member for cutting movement parallel to, and at a predetermined distance from, the convex face, this dermatome including mechanism for temporarily securing thereon a graft transfer member, for drawing the graft transfer member taut against the convex working face of the body member and for maintaining the tautness of the graft transfer member.

Thus, this prior disclosure involved the use of three elements and their respective functions, as follows: a clamp for holding one end of the graft transfer member to the dermatome, a rotatable shaft for holding the other end of the graft transfer member and for drawing it taut together with a cam for obtaining a finer adjustment of the tautness, and ratchets and pawls associated with the shaft and the cam for retaining the degree of tautness obtained.

In the invention of the present application, applicant has greatly simplified the mechanism of the second and third elements by combining them in a single element which performs the two functions of these two previously-proposed elements. To this end, applicant provides a worm and gear drive for the rotatable shaft which holds the second end of the graft transfer member, this worm drive not only obtaining, through the rotatable shaft, and without the use of the cam, arbitrarily small degrees of tautness in the graft transfer member, but also retaining any degree of tautness obtained, inasmuch as the worm prevents any reverse rotation of the shaft other than that imparted to it through the worm itself when it is desired to release the graft transfer member after cutting of the graft.

Therefore, another object of the invention is to provide, in a dermatome of the type adapted to have temporarily secured thereto a flexible graft transfer member, a single means for drawing taut such graft transfer member and retaining it at the degree of tautness selected.

A further object of the invention is to provide, in a dermatome of the type adapted to have temporarily secured thereon a graft transfer member, means for securing one end of such graft

2

transfer member to the dermatome and a rotatable shaft to which the other end of the graft transfer member may be secured together with a gear on the shaft and a worm cooperating therewith and by rotation of which the shaft may be turned to draw the graft transfer member taut against the working face of the dermatome.

These and other objects are effected by the invention as will be apparent from the following description and claims, taken in accordance with the accompanying drawings, forming a part of this application, in which:

Fig. 1 is a front elevational view, partially in section, of a dermatome constructed in accordance with the present invention;

Fig. 2 is a plan view of the dermatome shown in Fig. 1;

Fig. 3 is a fragmentary side elevational view showing details of the worm and gear drive for the rotatable shaft; and taken along the line III—III of Fig. 2, looking in the direction indicated by the arrows;

Fig. 4 is a transverse sectional view, taken along the line IV—IV of Fig. 2, looking in the direction indicated by the arrows;

Fig. 5 is a fragmentary side elevational view showing details of the blade-supporting structure;

Fig. 6 is a fragmentary plan view showing details of the clamping mechanism; and

Fig. 7 is a side elevational view of a crank handle by which the worm mechanism may be operated.

Referring now to the drawings in greater detail, particularly to Figs. 1 and 4 thereof, the reference character 10 indicates, in its entirety, a dermatome having a body member 11 comprised by a pair of spaced parallel side plates 12 and 13 of generally semi-circular shape, joined along their curved edges by a concavo-convex bottom plate 14. Preferably, the side plates 12 and 13 are provided with inwardly-directed flanges 15 against which the bottom plate 14 rests. These flanges 15 not only provide relatively extensive areas of engagement with the bottom plate, but also serve to stiffen the side plates and prevent deformation thereof.

Each side plate includes an upwardly-extending ear 16 having an opening 17 therethrough whose center coincides with the center of revolution of the concave working surface 18 of the bottom plate 14. A pair of bushings 19 are mounted in the openings 17 with flanges 21 abutting the outer surfaces of the side plates. A tubular handle 22 bridges the space between the

side plates and is supported on the inwardly-projecting bushings 19.

A shaft 23 is journaled in the bushings 19 for both rotary and reciprocatory movement relative to the body member 11 and has fixedly secured thereto a yoke, indicated in its entirety by the reference character 25. The yoke 25 includes a pair of parallel posts or arms 26, secured one at each end of the shaft 23 by tapered dowel pins 27 (Figs. 2 and 4) provided with threaded portions 28 threaded into bosses 29 on the posts 26 and having knurled finger pieces 30 for rotation of the pins. The other ends of the posts are joined by an integral cross bar 33 having a flat outer surface 34, between which and an opposed flat surface 35 on a blade clamping bar 36, a graft-cutting blade or knife 37 is adapted to be clamped (Figs. 4 and 5). As clearly shown in Fig. 4, the cutting edge of the blade 37 is positioned in close proximity to the convex working face 18 of the dermatome body member 11, and its spacing with respect thereto may be varied by changing a shim 38, between the blade and the surface 34 on the yoke cross bar 33, to one of greater or lesser thickness.

The blade-clamping bar 36 has a pair of studs 40 extending perpendicularly from its face 35 and extending through a pair of mating openings 41 in the outer ends 42 of the posts 26, which outer ends are offset with respect to the remainder of the posts with the result that the free ends of the studs 40 project beyond the post outer ends 42 and threadedly receive knurled finger pieces 43, by which the blade-clamping bar 36 may be drawn into clamping relation to the blade 37.

Preferably, each post 26 is provided with a projecting lip 45 restraining the finger pieces 43 against axial movement and insuring that rotation of the finger pieces will produce movement of the blade-clamping bar 36 towards or away from the yoke cross bar 33. This action is particularly desirable inasmuch as the posts are usually in the position illustrated in Fig. 5 when the blade is being assembled or removed, and without the lips 45 the blade-clamping bar would not stay spaced from the cross bar to permit of ready assembly of the blade and shim. The shim may be provided with a tab 46 on which its thickness in thousandths of an inch is indicated, so that the thickness of the graft that will be cut can be noted at any time.

One of the posts 26 is provided with a handle 47, by which the entire yoke 25, its shaft 23 and the blade may be simultaneously reciprocated and rotated to move the blade with a cutting motion relative to the working face of the body member, and at a predetermined distance therefrom.

The mechanism for retaining a graft transfer member taut against the convex working face 18 includes a clamp 50 mounted for limited pivotal movement on the pin 51 into and out of clamping engagement with the end A of a graft transfer member T (Figs. 2, 4 and 6). The graft transfer member-engaging edge of the clamp 50 is toothed or serrated, as at 52, to bite into the transfer member and insure that the latter does not pull out from between the clamp and the inner surface of the body member.

To retain the clamp in clamping position there is provided a rearwardly-extending arm 54, on top of which is a second arm 55, pivoted to the rear end of the first arm 54, as at 56. When the arm 55 is moved against the adjacent side wall

13, as shown in full lines in Fig. 6, it lies beneath a pin 57 which projects from the side wall 13, whereby the clamp 50 is prevented from pivoting about its pin 51 from clamping position. To release the clamp, the upper arm is moved away from the side wall 13 to the position indicated in Fig. 6 by the dot-dash lines, which movement is limited by a downwardly-extending lug 58 thereon (Fig. 4). To assist in moving the upper arm, the latter has an upwardly-extending finger piece or tab 59, which may be easily engaged by the fingers of the operator. The clamp 50 has a rearwardly-extending handle 60 by which it may be easily moved to and from clamping position.

15 The opposite end B of the graft transfer member T is received in the slot 63 of a spool 64 journaled in bearings 65 carried by the body member side walls 12 and 13. One of the spool journals projects outwardly beyond the adjacent side wall 13, as at 66, and has secured thereon a gear 67 meshing with a worm 68 secured on the shaft 69. This shaft 69 is mounted in a gear housing 71, attached to the side wall 13 by screws 72 and enclosing the worm 68 and gear 67. One end of the 20 worm shaft 69 projects through a top wall of the housing and is slotted, as at 73, for reception of a pin 74 extending diametrically of a socket 75 provided in the head 76 of a crank-type wrench 77, having a handle 78.

25 When the worm shaft 69 is rotated in a clockwise direction by means of the crank 77, the spool 64 will be turned counter-clockwise, as viewed in Fig. 4, thereby tightening the graft transfer member. It will be apparent that with the worm 30 drive, the spool 64 can be given any desired degree of rotation to produce any desired tautness in the graft transfer member, as distinguished from the arrangement in applicant's copending application, supra, wherein the minuteness of the 35 increments of rotation of the spool was limited by the pitch of the ratchet teeth thereon, and a cam was relied upon for smaller increments.

40 Furthermore, with the worm drive, no ratchet and pawl retaining mechanism is necessary to prevent counter rotation of the spool and consequent reduction in tautness of the graft transfer member. The worm itself locks the spool against rotation.

45 Application Serial No. 79,255 filed March 2, 50 1949, has been divided out of this application, the divisional application covering blade adjusting mechanism shown in Fig. 5.

55 While the invention has been shown in but one form, it will be obvious to those skilled in the art that it is not so limited, but is susceptible of various changes and modifications without departing from the spirit thereof.

What is claimed is:

60 1. A dermatome comprising a body member having a pair of side walls joined adjacent an edge by a bottom wall having a convex outer surface against which a flexible graft-transfer member is adapted to be held taut, means for holding one end of the graft-transfer member stationary 65 relative to the body member, bearing structure carried by the pair of side walls, a first shaft journaled in said bearing structure for rotation relative to the body member and having means for holding the other end of the graft-transfer member, whereby rotation of the shaft will draw the graft-transfer member taut against the convex outer surface of the body member bottom wall, said shaft having one of its terminal portions disposed exteriorly of the body member, a gear secured on said one terminal portion, a sec-

ond shaft supported by the body member, a worm secured on said second shaft and coacting with the gear on the terminal portion of the first shaft, whereby said first shaft may be rotated by the second shaft to draw the graft-transfer member taut, said coacting worm and gear preventing counter rotation of the first shaft due to torque applied thereto by the tautness of the graft-transfer member.

2. Structure as specified in claim 1, including 10 a handle for rotating the second shaft.
